(57) CLAIM

The ornamental design for a portion of an optical scanner, as shown and described.

DESCRIPTION

This application and application Ser. No. 29/051,765 are both copending reissue applications of the same original patent Des. 336,078 issued June 1, 1993.

FIG. 1 is a right side perspective view of a portion of an optical scanner showing my new design; and,

FIG. 2 is a top plan view thereof. [.]

FIG. 3 is a right side elevational view thereof, the left side elevational view being a mirror image; [.]

FIG. 4 is a front elevational view thereof; [.]

FIG. 5 is a rear elevational view thereof; and, [.]

FIG. 6 is a bottom plan view thereof. [.]

[FIGS. 2–6 are drawn on an enlarged scale.]

The scanner housing is shown in broken lines in the figures for illustrative purposes only and forms no part of the claimed design.
